Andrew W. Chu(57) **CLAIM**

The ornamental design for a beer glass, as shown and described.

DESCRIPTION

Fig. 1.1 is a back elevation view of a beer glass showing my new design;

Fig. 1.2 is a left side elevation view thereof;

Fig. 1.3 is an upper perspective view thereof;

Fig. 1.4 is a front elevation view thereof;

Fig. 1.5 is a top plan view thereof;

Fig. 1.6 is a bottom plan view thereof; and

Fig. 1.7 is a right side elevation view thereof.

The oblique shade lines in the drawings depict a surface that is transparent.
